(57) **CLAIM**

The ornamental design for a fan housing, as shown and described.

DESCRIPTION

FIG. 1 is a perspective view of the invention, with interior fan blades omitted for ease of illustration;

FIG. 2 is a front view thereof;

FIG. 3 is a rear view thereof;

FIG. 4 is a view looking from the right side of FIG. 8;

FIG. 5 is a view looking from the left side of FIG. 8;

FIG. 6 is a top view; and,

FIG. 7 is a bottom view.

The broken line showing of the attachment member and other portions is included for the purpose of illustrating environmental structure and forms no part of the claimed design.
